[57] CLAIM

The ornamental design for a charging unit for a battery powered device, as shown and described.

DESCRIPTION

FIG. 1 is a top, front, right hand side, perspective view of a charging unit for a battery powered device showing our new design;

FIG. 2 is a front elevational view thereof;

FIG. 3 is a rear elevational view thereof;

FIG. 4 is a left hand side elevational view thereof;

FIG. 5 is a right hand side elevational view thereof;

FIG. 6 is a top plan view thereof;

FIG. 7 is a bottom plan view thereof; and,

FIG. 8 is a top, rear, right hand side perspective view of a second embodiment of a battery charger showing our new design.

The broken line showing of the cord and adapter is included for the purpose of illustrating environmental elements only and forms no part of the claimed design. Except for the cord and strain relief, the other views of the second embodiment are identical to FIGS. 1-7.
